ATTORNEY.S

UNITED STATES PATENT OFFICE.

STEPHEN KOSTSZEWSKI, OF NEW YORK, N. Y., ASSIGNOR TO ROBERT FINDLAY MANUFACTURING COMPANY, OF NEW YORK, N. Y., A CORPORATION OF NEW YORK.

DESIGN FOR AN ARM FOR LIGHTING-FIXTURES.

57,674.

Specification for Design.

Patented Apr. 26, 1921.

Application filed September 14, 1920. Serial No. 410,348. Term of patent 7 years.

To all whom it may concern:

Be it known that I, STEPHEN KOSTSZEWSKI, a citizen of the United States, residing at New York, in the county of New York and State of New York, have invented a new, original, and ornamental Design for an Arm for Lighting-Fixtures, of which the following is a specification, reference being had to the accompanying drawing, forming part hereof.

The figure is a perspective view of an arm for lighting fixtures, showing my new design.

I claim—

The ornamental design for an arm for lighting fixtures, as shown.

STEPHEN KOSTSZEWSKI.
